Patent to be valid for a term of 14 years from the date of filing, or for 17 years from the date of issuance if a patent is granted on the application, whichever comes first. The term of 14 years will be reduced by 1 year for each year during which the application is pending.

UNITED STATES PATENT OFFICE

2,066,858

TIltABLE WINDOW VENTILATOR

James Sannita, East Chicago, Ind.

Application December 10, 1935, Serial No. 53,795

4 Claims. (Cl. 98—99)

My invention relates to improvements in tiltable window ventilators and it more especially consists of the features pointed out in the claims.

The purpose of my invention is to provide a window ventilator that may be made as a unit for standard width windows or adjustable lengthwise for different width windows and at the same time may be tilted to different positions so as to adapt it to varying weather conditions; that is easily applied and as easily removed whenever desired; and that provides a plurality of louvres on one face of the ventilator.

With these and other ends in view I illustrate in the accompanying drawing such instances of adaptation as will show the broad underlying features of the invention without limiting myself to the specific details shown thereon and described herein.

Fig. 1 is an elevation in section of a ventilator installed in a window, showing in dotted lines, 20 the ventilator adjusted to different positions.

Fig. 2 is an elevation of an end support.

Fig. 3 is a section on line 3—3 of Fig. 2.

Fig. 4 is a section on line 4—4 of Fig. 2.

Fig. 5 is a plan view of a two-member ventilator for endwise adjustment.

Fig. 6 is a diagrammatic section of a two-member ventilator.

Fig. 7 is a fragmentary plan view of the left hand end of a one-piece ventilator which includes 30 the end portions.

In producing my ventilator I may use whatever alternatives or equivalents of structure that the exigencies of various conditions may demand without departing from the broad spirit of the 35 invention.

I form the ventilator with right and left hand ends 1. For stiffening purposes these may have inwardly projecting flanges 2. They are provided with long slots 3 and a short slot 4 extending approximately perpendicularly to the long slot. At the end 5 of the long slot it is enlarged so that the head 17 of the pivot screw may pass thru the opening when a two-member ventilator 45 is to be removed from the window.

The ends 1 thru the medium of pivot screws 17 and nuts 29 hold the ends against the supporting plates 10. The pivot screws 17 pass thru slots 13 in these plates. The plates 10 are formed 50 lengthwise thereof with a U-shaped projection 11 and parallel thereto with a narrow U-shaped channel 12 in which any suitable felt or other packing 14 may be placed. On the projection 11 below the long slot 13 a convex circular enlargement 15 is formed. A corresponding concave

area 16 is formed on the ends. There are several different locations for these concave areas, the purpose of which is to hold the ventilator in the different tilttable positions I, II, and III shown in Fig. 1.

The ventilator proper is formed of a single sheet 6, which is bent to include the inwardly projecting angle of the ends. The sheet 6 forms two sides of the ventilator, the third side being open toward the exterior of the window and the upper portion of the sheet 6 has bent-up louvres 7 adjacent the openings 8. It may have a bottom flange 9, if desired, which flange may rest against the window stool 25. The sheet 6 may be spot welded onto the flanges 2 of the ends. When the ventilator is formed of two members the second member may have its edges folded at 28 so as to be retained on the other member in slidable relation.

As assembled the ventilator may be in the 20 different positions I and III shown in Fig. 1 with the sash 18 lowered so that its bottom edge will meet the upper edge of the ventilator. When the ventilator is shifted into the position II the sash 18 may be lowered correspondingly. In the position I the pivot screws are at the ends 5 of the long slots 3. When it is in the position III, the pivot screws 17 will be at the other end of the long slot and when the ventilator is in the position II the pivot screws will be at the upper end 30 of the short slots 4. The ventilator may be, if desired, positioned at points between the location of the concave area 16.

The supporting plates 10 are held on the inside stop 22 by screws or otherwise. The window sash 35 18 slides in the lower sash channel 31 and the upper sash channel 20 is separated from the other channel by the parting strip 19. On the outside of the upper sash channel the usual outside stop 23 is placed in the window frame 27 and the stool 40 25 on which the ventilator may rest is positioned on the inner edge of the window sill 24. In the extreme outward adjustment III of the ventilator, it will not interfere with the screen frame 26.

When the ventilator is in the position I the air 45 currents will be directed practically parallel to the inside of the window in a vertical direction especially adaptable to stormy weather. For pleasant and less stormy weather it may be tilted into the positions II and III, and modifications 50 of these positions may be secured by tilting the ventilator on the pivot screw to intermediate positions. In such positions there will be sufficient tension endwise of the ventilator on the end plates between the raised surfaces 15 and 16 to 55

hold the ventilator against sliding to another point.

In Figs. 1, 4, 5, and 6, the ventilator is shown with separate ends 1. If desired, it can be made 5 altogether in one piece so as to include the end portions as shown in Fig. 7. The sheet 6 is bent at 34 lengthwise of the ventilator and perpendicular to this the triangular end portions 31 and 32 are bent at 30 perpendicular to the face of the 10 sheet 6. These triangular portions 31 and 32 are formed the same at both ends of the sheet and the portion 31 has formed therein the long slots 3, short slot 4 and an enlarged opening 5 at the end of the slot 3. The triangular portion 31 15 may have an extension 33 which will overlap the triangular portion 32 on its inside or outside as desired. Where the two portions 32 and 33 overlap they may be spotwelded to each other and two of the convex portions 16 may be formed on this 20 overlap.

What I claim is:—

1. In tiltable ventilators, a triangular shaped end plate having a long slot formed therein and a short slot perpendicular thereto, a plurality of 25 concave-convex areas on the end plate, a supporting plate, a raised projection thereon said projection having a lengthwise slot, a reverse groove formed lengthwise of the plate, a felt packing in the groove, a pivot screw passing thru the 30 slots of the end plate and into the slot of the supporting plate, and means for retaining the pivot screws against accidental displacement.

2. A tiltable ventilator comprising a member closed on the ends and on two sides one of which is louvered and open on one side, a pair of supporting plates, and means for selectively holding the ventilator in different tiltable positions on the 5 supporting plates beneath a raised window to limit the passage of air through the louvres.

3. A tiltable ventilator of triangular cross-section closed on two sides one side of which is provided with louvres and a third side remaining 10 open, flanged ends to which the two sides are secured, a pair of slotted supporting plates secured to the window frame, and means for pivoting the ventilator adjacent the inside window stops on the plates in a plurality of positions. 15

4. A tiltable ventilator having a plurality of longitudinal parallel faces one face being open and the other faces being closed, louvres formed in one face adjacent a closed one, closed ends to the ventilator, a frame, a bottom member of the frame, a 20 sliding closure in the frame, means for pivoting the ends of the ventilator to the frame above its bottom member, and means for retaining the free edge of the closed face that is adjacent the louvered face in engagement with the bottom member 25 of the frame while the free edge of the louvered face is in engagement with the opened sliding closure so as to thereby prevent the passage of air past the closure opening except through the louvered face regardless of the angular relations of 30 the faces to the frame.

JAMES SANNITA.
